(57) **CLAIM**

The ornamental design for a trocar and trocar actuation mechanism, as shown and described.

DESCRIPTION

FIG. 1 is a top plan view of a trocar and trocar actuation mechanism, showing my design;

FIG. 2 is a front elevational view thereof; the rear elevational view being a mirror image of the front view shown;

FIG. 3 is a right side elevational view thereof;

FIG. 4 is a left side elevational view thereof;

FIG. 5 is a bottom plan view thereof; and,

FIG. 6 is a top left rear perspective view.

The phantom line showing in the drawings is for illustrative purposes only and forms no part of the claimed design.
